WASHBASIN

Elbert A. Corbin, Jr., Lansdowne, Pa., assignor
of one-half to William C. Biddle, Lansdowne,
Pa.

Application December 7, 1937, Serial No. 178,483

1 Claim. (Cl. 4—166)

My invention relates to a new and useful wash-basin and it relates more particularly to a wash-basin of an extremely simplified construction whereby the cost of manufacture, as well as the cost of maintenance, is greatly reduced.

My invention still further relates to a wash-basin having a concealed overflow, and one in which the valves for controlling the water supply as well as the waste are so positioned as to be out of the way and at the same time greatly to facilitate manipulation.

In the accompanying drawing:

Fig. 1 represents a top plan view of a wash-basin embodying my invention.

Fig. 2 represents a rear elevation of Fig. 1.

Fig. 3 represents, on an enlarged scale, a section on line 3—3 of Fig. 1.

Fig. 4 represents, on an enlarged scale, a plan view of the connection between the waste plug and the drain.

Fig. 5 represents, on an enlarged scale, a section on line 5—5 of Fig. 1.

Fig. 6 represents, on an enlarged scale, a section on line 6—6 of Fig. 3.

Fig. 7 represents, on an enlarged scale, a fragmentary sectional view on line 7—7 of Fig. 3.

Referring to the drawing in which like reference characters indicate like parts, my novel washbasin comprises the bowl 1 which may be of any desired shape or size and which is provided with the waste outlet 2 in which is positioned the removable screen 3. The bowl 1 is provided with an upper extension 4 of the back wall thereof, which extension 4 merges into the horizontal portion 5. In the horizontal portion 5 are formed the three elongated pockets 6, 7 and 8 which receive the handles 9, 10 and 11 for operating the water supply valves 12 and 13 as well as the waste plug 14. Since the valves 12 and 13 are identical except that one is for supplying hot water and the other for supplying cold water respectively from the pipes 15 and 16, I have only shown the detailed construction of one of the valves in Fig. 5.

Referring to Fig. 5, which is a vertical section through the valve 13, it will be seen that the valve comprises a casing into which the water is supplied by the pipe 16 and to which is positioned the vertically sliding valve construction consisting generally of oppositely disposed washers 18 and 20 supported by the plates 21 which are mounted on the stem 22 so that, when the handle 11 is in its lowermost position or substantially flush with the top of the horizontal portion 5, the valve is in the closed position. If it is desired

to open this particular valve, the handle 11 is raised upwardly until the lower washer 18 and its supporting plate 21 partly or wholly clear the orifice of the pipe 16. This permits the water to flow downwardly into the horizontal pipe 24 which is suitably coupled as at 25 to the inlet 26 of the mixing chamber 27. The mixing chamber 27 terminates in a spout or nozzle 28 which discharges the water into the bowl 1. By raising the handles 9 and 11 to the desired extent, the proper mixture of hot and cold water is obtained, and, when it is desired completely to shut one or the other or both, it is merely necessary to push the handles 9 and 11 down as far as they will go, or until the bottom plate 21 rests upon the shoulder 23.

In order to operate the waste plug 14 it is necessary to manipulate the handle 10. Referring to Fig. 3 it will be seen that when the handle 10 is in its raised position the plug 14 rests upon its seat and prevents the water from entering into the chamber 30 which communicates with the drain 31. In this position of the parts the water in the bowl 1 will rise in the pipe 32 until the top 33 of the partition 34 is reached, whereupon, if the valves 12 and 13 are not closed, any additional water entering the bowl 1 will flow over the edge 33 of the partition 34 into the pipe 35 which, at its bottom, communicates with the drain 31 thus preventing the level of the water 30 in the bowl from rising at any time to a level higher than the top 33 of the partition 34. If it is desired to open the drain plug and permit the water to flow from the bowl 1 directly to the drain 31, it is merely necessary to press the handle 10 down in the pocket 7. This results in pushing the stem 36 of the plug 14 upwardly through the action of the link 37 which is fulcrumed at 38 to a support 38a and pivoted at 39 to the stem 40. The link 37 is preferably secured to the bottom of the stem 36 as best seen in Fig. 7, there being a pin 41 passing through the stem 36 and the bearing 42 so that, if it is necessary for cleaning or repair to dismantle the waste plug 14, it is merely necessary to remove the pin 41, whereupon, the stem 36 and the plug 14 can be detached from the link 37 and drawn upwardly through the waste opening 2, it being understood that the screen 3 has already been removed. Similarly, by unscrewing the valve cap 43 and the coupling 25, access is immediately had to the interior of the valve 12 or 13. It will be noted that I utilize a "safe closing" valve construction, and that, when the water enters under pressure through the inlet 16 as best seen in Fig. 5, the
